MEANS FOR ADAPTING DECIMAL ACCUMULATORS TO NONDECIMAL SYSTEMS OF NOTATION

Robert H. Strother, Brooklyn, N. Y., assignor to Remington Rand Inc., New York, N. Y., a corporation of Delaware

Application June 22, 1949, Serial No. 100,682

4 Claims. (Cl. 235—60)

1

This invention relates generally to accounting machines and more particularly to accumulators for such machines, especially those capable of accumulating amounts according to a plurality of number systems.

The principal purpose of the invention is to adapt accumulators of a certain type which ordinarily handle numbers according to one system of notation to add and subtract numbers in another system of notation, usually, to adapt a decimal accumulator to adding and subtracting also non-decimal fractions. In some prior machines the non-decimal wheels have been made of the same pitch diameter as the decimal wheels but divided circumferentially into twelfths or eighths or whatever the fraction may be, thus bringing the teeth of said fractional wheels closer together or farther apart, or, in other words, changing their diametral pitch. This made it necessary to change the pitch of the actuating rack which again necessitated changing the stops for controlling said rack. Thus adding a fraction wheel to a decimal accumulator necessitated making considerable changes in the means for actuating the wheels. According to the present invention the fraction wheels are made of substantially the same diametral pitch as the decimal wheels, thus obviating the necessity for changing the actuating mechanism.

This makes the fraction wheels larger or smaller than the decimal wheels which calls for changes in the manner in which these wheels are journaled in the accumulator.

Moreover the angular spacing of the non-decimal wheel is different from that of the decimal wheels, the teeth being spaced 36° apart in a ten-tooth wheel, 30° apart in a twelve-tooth wheel, 45° apart in an eight-tooth wheel, etc. This presents a problem in bringing the teeth of the wheels into proper angular positions for engagement with their racks in shifting between addition and subtraction. The accumulator and its racks are built primarily for ten-tooth wheels, and when a non-decimal unit is added and so set as to engage its rack properly in subtraction the teeth will, unless provision is made to the contrary, not come at the right angle for proper engagement with the racks when shifted to addition. The invention includes means to overcome this.

One of the purposes had in mind in the invention has been, when adding fraction wheels to the accumulator, to confine the necessary changes as far as possible to the accumulator itself, with no change at all or none but very simple ones in the rest of the machine.

One object of the invention is to so construct the fractional denomination of the accumulator that it can receive a tens carry from another denomination as well as transmit one to the next

2

order to the left, so that the fractional section of the accumulator is not necessarily the extreme right hand section, but may be located anywhere desired in the accumulator. Also, where it is the extreme right hand section, it may receive a carry from the wheel of highest order so as to add or subtract the fugitive one and thus preserve the so called algebraic feature of the accumulator. This also enables the use of more than one fractional wheel in an accumulator. Thus, if the fraction is twelfths the last two sections may be for adding twelfths, thus enabling the addition and subtraction of gross, dozens, and twelfth dozens. Also, by putting two carry teeth on each twelve-tooth wheel, this section will add sixths, and if made the second wheel of the accumulator it will add sixtieths in order, for example, to add workmen's time in hours and minutes.

20 The fact that by the present invention the fractional section or sections may be placed wherever desired in the accumulator, and that more than one of them can be used in the same accumulator, adds importance to the making of 25 the fraction wheels of the same pitch as the decimal wheels, and confining the adaption of the accumulator to fractions almost exclusively to the accumulator itself.

One machine in which the difficulty of changing the actuating mechanism is great, is the tabulator disclosed in the patent to W. W. Lasker and John Mueller, 2,323,816, and the patent to John Mueller, 2,381,361, and it has long been desired to enable certain denominational orders 35 of the accumulators of this machine to handle fractional amounts, for example, twelfths, so as to condition the machine for accumulating British currency or amounts in dozens and twelfth dozens.

40 For purpose of illustration and description the invention is disclosed as applied to the Lasker and Mueller machine, but it is to be understood that the invention is applicable not only to other decimal accumulators, but also to accumulators 45 for accumulating amounts according to other number systems.

One object of the invention is to provide means whereby the ordinary wheels in one or more denominational orders of an accumulator can be 50 replaced by wheels having a greater number of teeth of the same pitch.

Another object of the invention is to so construct said means as to enable a common setting member to move the unlike wheels through different angular distances in setting the accumulator for subtraction or addition, so as to bring all of the wheels into their proper positions relative to the actuators.

Still another object of the invention is to so modify the accumulator generally as to secure

proper cooperation between the changed and unchanged orders thereof.

To these and other objects which will become apparent during the course of the description, the invention consists chiefly in replacing one or more orders of accumulator wheels having one number of teeth with other wheels having a greater number of teeth of the same pitch, replacing the parallel movement carriers with non-parallel movement wheel carriers, and providing one of the latter carriers with an eccentric connection to the common operating member, whereby the wheels supported by said carrier and its associate are moved through different angular distances than the wheels carried by the parallel carriers in setting the accumulator for addition or subtraction.

In the drawing:

Fig. 1 is a right hand elevation of the known accumulator with fragments of the mechanism for operating it;

Fig. 2 is a partially diagrammatic fragmentary view of one denominational order of the known accumulator, and which in conjunction with Fig. 3 serves to illustrate certain differences in the movements of the known mechanism and the mechanism of the invention;

Fig. 3 is a partially diagrammatic fragmentary view of a denominational order of the known accumulator to which the principles of the invention have been applied;

Fig. 4 is a sectional view from the right illustrating the known mechanism in the highest order of the accumulator and the manner in which said mechanism is modified in accordance with the invention;

Fig. 5 is a fragmentary sectional view from the right, illustrating the mechanism of the invention in the units order of the accumulator with the accumulator set for subtraction and with certain of the known mechanism in tens order shown in dotted lines to emphasize the differences in the two mechanisms;

Fig. 6 is a view similar to Fig. 5 but on a larger scale and with the accumulator set for addition, the mechanism in tens order being shown more fully and emphasized by cross-hatching in this figure; and

Fig. 7 is an isometric view on a large scale showing the construction of part of the mechanism of the invention.

The accumulator to which the invention is here shown applied is substantially identical with that disclosed in the above cited patents, and will be described along with certain of the mechanism for operating it, before entering into a detailed description of the improvements.

The accumulator has a stationary frame comprising right (nearest the observer in Fig. 1) and left hand frame plates 100 rigidly connected together by bolts 101. A shaft 102 passing through said plates has a bell-crank 103 fast on its right hand end, and a similar bell-crank fast on its left hand end (Fig. 4). Journaled in the upstanding arms of said bell-cranks are the ends of a rod 104 constituting the pivot of a rocker operatively identical with the one shown in the patents, but of differently detailed construction. Said rocker comprises two end pieces 105, one inside each of the bell-cranks 103 and upper and lower pivot rods 106 mounted in the end pieces 105. On the upper rod 106 there are pivoted the right and left hand side plates 107 of an auxiliary frame, which also includes cross members 108. A similar frame but upside down of the first, has its

side plates 107 pivoted on the lower rod 106. Near their rear ends the upper and lower side plates 107 (both right and left hand) are loosely connected by a link 110 pivoted to the plates at 111. The links 110 are parallel to the end pieces 105, and the pivots 111 of the former are the same distance apart as the pivot rods 106 of the latter. The upper and lower auxiliary frames are, therefore, connected together into a linkage which is in the form of, and, in effect, is a parallelogram. Each of the links 110 has a trunnion 112 by which it is pivoted to a supporting link 113 pivoted at 114 to the stationary frame plate 100, this link 113 being parallel with and equal in length to the upstanding arms of the bell-cranks 103. The construction is such that the upper and lower auxiliary frames can be moved in opposite but parallel directions from their add position shown in Fig. 1 where the lower frame projects further rearward to their subtract position (see Fig. 5) and where the upper frame rather than the lower projects further rearward (rightward in Fig. 1) by rocking the rocker 104, 105 about its pivot; and, in whichever of their two relative positions the frames are, both can be moved bodily rearward together by swinging the bell-cranks 103 clockwise and carrying the links 113 with them. In Fig. 1 the accumulator is shown set for addition with the lower frame 107 set further rearward. If it is desired to subtract a number the rocker 104, 105 will first be rocked clockwise about its pivot to project the upper frame toward the racks 115 and to withdraw the lower frame, and then both frames will be moved together by swinging the bell-cranks 103 so as to bring the upper register wheels into mesh with the racks.

The accumulator comprises a suitable number of upper subtract wheels 116 and lower add wheels 117 constantly in mesh as shown in Fig. 2. Each of the wheels is mounted on the rearward end of a lever or carrier 118, said levers being pivoted on the rods 106 where they are spaced apart by spacing washers. The construction is such that when the rocker 104, 105 is rocked, the carriers 118 and wheels 116 and 117 will partake of the relative fore and aft movement of the frames 107.

In each denomination the two carriers 118 are connected together by a link 120 pivoted at 121 and 122 to the carriers. Link 120 is parallel with the links 113 and end pieces 105, and its pivots 121 and 122 are the same distance apart as the rods 106. This link 120 causes the register wheels, when they are relatively shifted for addition and subtraction, to roll one on the other, their axes being maintained at all times at a uniform distance apart.

In order to effect the transfer of tens each pair of carriers 118 is moved upward at its rearward end (Fig. 2) to the extent of one tooth space, the wheel 116 or 117 which is at that time in mesh with the rack rolling on said rack.

To this end each upper carrier 118 is extended upward at its rearward end and is guided in a comb formed on one of the cross frame plates 108 (Fig. 4) and the reverse construction applies to each lower carrier 118. In the normal position of the parts a shoulder 123 on the lower carrier 118 rests on the upper edge of a cross frame plate 108, and a similar shoulder 124 in the upper carrier 118 stands below another frame plate 108 a distance equal to one tooth space of the rack 115. The carriers are at the proper times put under spring tension tending to rock

them counter-clockwise, but are normally held down by latches which are tripped by the wheels of next lower order passing from 9 to 0. In all of these movements the two carriers are constrained to move in harmony by their connecting link 120. When the parts are set for addition as in Fig. 4, shouldered notches 129 in the lower carriers 118 are engaged by transfer latches 125 pivoted on a cross rod 126 mounted in the auxiliary frames 107, said latches having springs 127. Each latch is connected by a link 128 with a bell-crank transfer pawl 130 pivoted to the lower carrier 118 in position to be operated by a carry tooth 131 on the appropriate register wheel 117. The construction is such that during addition on the down stroke of the racks, when one of these wheels turns from 9 to 0 the tooth 131 rocks the pawl 130 and withdraws the latch 125 for the next higher pair of carriers. In total taking, where the total is positive the carry pawl 130 arrests the counter-clockwise rotation of the wheel at zero.

The transfer mechanism used in subtraction cooperates with the upper register wheels 116, and comprises in each denomination a latch 132 spring pressed into engagement with a shouldered notch 133 in the upper carrier 118, and withdrawn by a link 134 connected to a bell-crank transfer pawl 135 pivoted to the carrier and adapted to cooperate with the transfer tooth 136 on the register wheel. Each link 128 has at either end a nose 137 adapted to cooperate cam fashion with inclined shoulders on the proximate edges of the lower and upper transfer pawls 130 and 135 in suchwise that, when the parts are set for addition, the upper nose 137 forces the pawl 135 upward away from the wheel and pulls the latch 132 out of engagement, leaving the transfer mechanism entirely under control of the lower wheels. When the parts are set for subtraction the link 128 rocks about its two pivots and the upper nose 137 allows the upper transfer pawl to drop down to operative position, whereas the lower nose 137 cams the transfer pawl 130 downward to inactive position, withdrawing latch 125 from engagement. This leaves the transfer entirely under control of the upper wheels.

In the upper set of transfer devices, the latch 132 in lowest order and a similar device 138 operated by the pawl 135 of highest order are made in the form of bell-cranks whose horizontal arms engage open ended slots in the arms of a yoke or bail 141 pivoted to the frame plates 107 at 142. The construction is such that, when the highest order wheel passes from 9 to 0, its pawl 135 rocks bell-crank 138 and, thereby, bail 141 which draws the latch 132 from the lowest order lever 118, permitting the units wheel 116 to move upward and subtract the "fugitive one." Similar "fugitive one" devices are included in the lower transfer devices, and negative totals are, therefore, registered in their true amounts.

In order at the proper time to place the carriers 118 under spring tension to predispose them to transferring operations, each upper carrier is prolonged forward of its pivot 106 (Fig. 4) and has pivoted thereto at 143 a bell-crank 144 whose depending arm is connected by a spring 145 with the forward end of carrier 118, tending to rock said bell-crank clockwise until arrested by an ear 146 formed on the carrier. It will be perceived that if the forward end of said bell-crank be pressed down, the spring 145 will tend to rock the carriers 118 counter-clockwise, but if the for-

ward end of the bell-crank be allowed to rise until arrested by ear 146 this tendency disappears. The forward end of each said bell-crank carries a roller 147 lying beneath a cross bar 148 (Fig. 1) which, as described in the aforementioned patents, is normally in its upper position but is moved down, and remains down substantially during the time the totalizers are in mesh with the racks in computing operations.

- 10 In order to move the totalizers into and out of mesh with the racks and to shift the accumulator for addition or subtraction the right hand (nearest the observer in Fig. 1) upper and lower auxiliary frame plates 107 have pivoted thereto 15 at 150 an upper push link 151 and a lower push link 152, respectively. For safety reasons these links are made up of two pieces connected by pins and slots and drawn in opposite directions by a spring 153. Normally the upper link rests 20 on a lug of the lower link to which it is connected by a spring 154, but, on occasion, the two links are spread apart. The upper link is made with a shoulder 155 and the lower link with a shoulder 156 for alternative engagement by a pin 157 carried between the two members of a compound arm 158 fast on a transverse rock shaft 160. As described in the aforementioned patents, shaft 160 is rocked counter-clockwise at suitable times 25 to engage the accumulator with the racks, pin 157 acting on the shoulder 156 for addition and on shoulder 155 for subtraction. If, as also described in said patents, the links 150 and 151 be swung downward for subtraction, then when the shaft 160 is rocked, the first part of its motion 30 will consist in pushing the links 151 and the upper frame plates 107 rearward, rocking the rocker 104 clockwise about its pivot, thus advancing the upper wheels 116 and withdrawing the lower ones 117 so that the actuation will be by the former 35 40 wheels. In this movement the relative motion of the upper and lower frame plates is limited by two lugs 161 projecting downward from the upper frame plate 107, and another lug 162 projecting upward from the lower frame plate 107.

45 Referring to Figs. 1 and 4, the register wheels when disengaged are held against turning by detents 163 consisting of long levers each pivoted at 164 to the appropriate carrier 118 and pressed by a spring 165 against the upper wheel 116. At 50 the time when the wheels are shifted between addition and subtraction, therefore, the upper wheels are held against rotation and the lower wheels roll under them. As soon as the relative motion of the auxiliary frames 107 is completed, the further rocking of the pin 157 forces them to move rearward together.

55 Beginning with the parts in the position shown in Fig. 1, if the operation is one of addition, the pin 157 will move idly up to the shoulder 156, and its additional movement will cause the totalizer to engage the racks.

At the proper time the shaft 160 is rocked clockwise to normal position, whereupon the totalizer is withdrawn from the racks by means 60 of a spring 166 connected to the left hand bell-crank 103 (Fig. 4).

65 In order to release the detents 163 when the totalizer moves into engagement with the racks, each detent has a forwardly directed arm lying beneath and some distance from a bail bar 167 whose arms 168 are fastened on a rock shaft 170 journaled in upwardly extending ears of the upper auxiliary plates 107. The left hand arm 168 is extended forwardly from its pivot, and is connected by a link 171 with the horizontal arm,

of the left hand bell-crank 103 (Fig. 4). As this bell-crank moves clockwise in Fig. 4, to move the wheels into engagement, it rocks the bail bar 161 downward and at the last part of this movement said bail bar strikes the detent levers 163 and moves them out of engagement with the pinions. They are moved into engagement at the first part of the return motion of the totalizer.

All of the mechanism thus far described is substantially identical with that shown in the hereinbefore mentioned patents. However, before going on to a description of the changes made in said mechanism by the present invention, it is deemed desirable first to explain certain features of the old mechanism in a manner which it is expected will be beneficial to an understanding of the invention.

In Fig. 2, certain diagrammatic lines have been added to illustrate the angles and certain linear distances through which the various parts of the accumulator are moved by the motion of rocker 104, 105 in shifting from the add position to the subtract position. Angle "A" is the one through which the rocker 104, 105 is rocked, and in the illustrated accumulator is 54° , that is to say, 27° either side of a vertical through the center of pivot 104. As described hereinbefore, the distance between the centers of pivots 106 is equal to the distance between the centers of wheels 116 and 117, and, therefore, a line passing through the centers of said wheels and pivoting about the point of tangency of their pitch circles, will, by the movement of rocker 104, generate an angle equal to angle A. Thus, in the add position the wheels stand 27° counter-clockwise of vertical and in shifting to subtract positions rock clockwise 27° beyond vertical. And the opposite is true when shifting from subtract to add position.

Normally the upper wheel 116 is held by its detent with a tooth pointing along the horizontal axis thereof toward the rack, said tooth, because of the relative vertical positions of the rack and the accumulator, pointing into a notch of the former. Remembering that the upper wheel 116 is held against rotation by its detent with two of its opposite teeth standing horizontally, when shifting to addition the lower wheel rolls on the upper one and at 27° from the vertical two of its teeth will also stand in horizontal alignment this being due to the fact that the teeth are 36° apart. Also, when the wheels stand in these relative positions as shown in Fig. 2, the axis of the lower wheel is at a distance below that of the upper wheel, nearly equal to three tooth spaces of the rack. In the manufactured machine, the wheels are made slightly oversize so as to make this distance just equal to three rack teeth. In shifting back to subtract position the lower wheel rolls on the upper the same distance, but in the opposite direction. It is evident that if rocker 104, 105 and, therefore, wheels 116 and 117 are rocked relative to vertical some angle other than 54° the teeth of these ten-tooth wheels will not be brought into the desired relation with the rack. Therefore, in adapting one of the orders of this accumulator to the accumulation of twelfths the amount of rocking movement of the rocker 104, 105 cannot be altered.

In Fig. 2, B' denotes the linear distance through which the carriers are moved to bring the wheels to the proper position relative to the rack.

In those orders in which it is desired to accumulate twelfths, in the present instance the right hand or units order, the ten-tooth wheels are replaced with upper and lower, intermeshing twelve-tooth wheels 175 and 176 (Fig. 3) of the same pitch, and the parts concerned with the positioning of said wheels are modified to position them correctly relative to their actuators.

The twelve-tooth wheels are supported by carriers 177 (Figs. 3, 5, and 6) which unlike the ten-tooth wheel carriers are not elements of a parallel linkage. At its forward end the lower carrier 177 is pivoted in the preferred construction on the same rod 106 as the ten-tooth wheel carriers, but the upper carrier 177 is pivoted on an eccentric sleeve 178 mounted on the upper rod 106 and fixed to rock on said rod in unison with and through the same angles as the rocker 104, 105, that is to say, 54° (Fig. 2). In the present instance the sleeve is journaled on the upper rod 106 and is welded or otherwise fastened to a fixture 179 (see also Fig. 7) which extends around the pivot 104 and has its lower end loosely mounted on the lower rod 106. Thus the eccentric is constrained to rock with rocker 104, 105 and in so doing moves the upper carrier 177 a greater distance than the lower one is moved. The amount of eccentricity of sleeve 178 is, of course, dependent on the amount of movement it is desired to impart to the upper carrier over and above the amount which the lower carrier is moved, which is the same as that through which the ten-tooth wheel carriers are moved.

Just forward of the wheels 175 and 176 the two carriers are connected by a link 180 whose pivots 181 and 182 are spaced apart a distance sufficient to maintain said wheels in their correct meshing relation with one another.

In the present instance the distance between the centers 183 and 184 of the wheels is greater than the distance between the centers of eccentric 178 and lower rod 106, which results in that the pivots 181 and 182 are spaced apart a distance somewhere between the two but equal to neither.

The lower carrier 177 is provided with a shoulder 185 (Figs. 3, 5, and 6) like the shoulder 123 (Fig. 2) of a lower ten-tooth wheel carrier 118 and, like the latter, rests on the lower cross frame bar 108 to support the upper and lower carriers. However, the pivot 184 of the lower twelve-tooth wheel is situated lower than the pivot 187 of a ten-tooth wheel a distance appropriate to locate the center 183 of the upper twelve-tooth wheel 55 in horizontal alignment with the center 186 (Fig. 5) of the adjacent upper ten-toothed wheel and, therefore, in horizontal alignment with the middle of a notch in the rack when the accumulator is set for subtraction, and to locate the center 184 of the lower twelve-tooth wheel one half tooth space of the rack below the center 187 of the adjacent lower ten-tooth wheel (Fig. 6) and, therefore in horizontal alignment with a tooth of the rack when the accumulator is set for addition. The centers 183 and 184 of the twelve-tooth wheels are, of course, situated a short distance further away from the racks than the centers 186 and 187 of the ten-tooth wheels because of the greater diameter of the former wheels.

It will be remembered that in the ten-tooth section of the accumulator a tooth of the upper and a tooth of the lower wheel point horizontally into notches of the rack, the lower notch be-

ing three below the upper one. The upper twelve-tooth wheel is held by its detent with a tooth pointing horizontally toward the rack, and, when the accumulator is set for subtraction, pointing into the same notch of the rack as the horizontal tooth of a ten-tooth wheel. The teeth of the twelve-tooth wheels are spaced 30° apart which results in that, in the add position of the accumulator, if the wheels are positioned 30° counter-clockwise of vertical, a line connecting the centers of said wheels bisects a tooth of the upper wheel and the notch of the lower wheel with which said tooth is meshing (Figs. 3 and 6); and moving around the lower wheel, a notch thereof if aligned horizontally with the tool of the rack immediately below the notch engaged by the horizontal tooth of the adjacent lower ten-tooth wheel.

With the wheels in the add position (Fig. 6) it will be noted that center 183 of the upper twelve-tooth wheel is positioned a short distance below that of the adjacent ten-tooth wheel, which results in that the horizontal tooth of the former does not point into the appropriate notch of the rack. This, however, is of no consequence as the upper wheel, when in add position, never engages the rack; and the same holds true for the lower wheel when the wheels are set for subtraction, that is to say, when the accumulator is set for subtraction (Fig. 5) a notch of the lower wheel does not point horizontally at a tooth of the rack, which again is of no consequence as the wheel does not engage the rack in this position.

In shifting the accumulator from its add position to its subtract position, the upper twelve-tooth wheel rocks from its 30° counter-clockwise of vertical position, clockwise beyond vertical to a position where its horizontal tooth is aligned horizontally with a notch of the rack and situated the proper linear distance from the rack. In the present instance, the upper wheel moves to a position $23^\circ 26'$ clockwise or vertical. In Fig. 3, B' denotes the distance which the upper carrier is moved, such distance being greater than distance B (Fig. 2) an amount sufficient to bring the upper twelve-tooth wheel into the proper position relative to the rack when in subtract position, and in add position to bring its center 30° counter-clockwise from the vertical. The lower twelve-tooth wheel carrier is moved the same distance as a ten-tooth carrier. The angle A' generated by a line through the centers of lower rod 106 and eccentric 178 is, of course equal to 54° , the same as angle A (Fig. 2). It is evident, therefore, that the amount of eccentricity of sleeve 178 is so designed as to cause the rocking of rocker 104, 105 through, in the present instance, an angle of 54° to move the upper carrier the proper linear distance and, therefore, the wheels 175 and 176 through an angle of $53^\circ 26'$. It will be understood, however, that in other instances the angles through which the rocker moves or the linear distance through which it is desired to move the upper carrier would differ and, therefore, the amount of eccentricity of sleeve 178 would differ accordingly.

It is believed evident from the foregoing that more than one twelve-tooth section can be inserted in an accumulator and that the twelve-tooth wheels are actuated by rack bars identical with those which actuate the ten-tooth wheels. In fact, the same racks used for ten-tooth wheels can, by shifting the accumulator laterally as described in the aforementioned patents, be used for twelve-tooth wheels.

The detent 188 for the upper twelve-tooth wheel 175 is like and operates in the same manner as the detent 163 for a ten-tooth wheel 116.

The transfer mechanism associated with the twelve-tooth wheels has been modified somewhat in a manner presently to be described from that described hereinbefore with reference to the ten-tooth wheels.

The upper carrier 177 is provided with a shoulder 190 which, by engaging the upper frame bar 108, limits the upward movement of the carriers in transfer operations. Shoulder 190 is made on two levels connected by an incline and so situated as to allow the carriers to move upward a distance sufficient to rotate the associate wheels one tooth space, whether the upper carrier is in its lower add position (Fig. 6) or in its higher subtract position (Fig. 5) at the time. The frame bar 108, it will be remembered, shifts through the same distances as the ten-tooth wheel carriers and relative movement occurs between shoulder 190 and said bar due to the action of eccentric 178 in moving the upper twelve-tooth carrier a greater distance, as is apparent from Fig. 6 where a ten-tooth section is shaded in behind a twelve-tooth section.

When the carriers are in subtract position (Fig. 5) the lower level of shoulder 190 engages the bar 108, but, when the parts are shifted to add position (Fig. 6) the upper carrier is positioned lower an amount equal to the vertical distance between the center 183 of the upper twelve-tooth wheel and the center 186 of the adjacent ten-tooth wheel, and the upper level of shoulder 190 is made to engage said bar when a carry occurs so as to limit the rotation of the twelve-tooth wheels to one-tooth space.

In the subtract position the carriers are held against transfer movements by a latch 191 which engages a notch 192 in the upper carrier. In case the twelve-tooth section is the right hand or units one the latch 191 is provided with a horizontal arm 193 operable by the "fugitive" bail 141 to withdraw said latch and free the carriers. As described hereinbefore, this bail is at its other end connected by bell-crank 138, and link 134 (Fig. 4) with the transfer pawl 135 which engages the highest order wheel 116, and when said pawl is cammed upward either by the carry tooth of said wheel or by the nose 137 of the associate link 120, said bail is rocked and withdraws the latch 191 (Fig. 5). A similar set of devices (Fig. 6) is provided for controlling the carriers 177 when the accumulator is set for addition. However, the lower latch 191 is shortened to avoid any possibility of interference with the lower carry pawl 195 which itself is appreciably lower in the machine, than the corresponding pawl of a ten-tooth section.

In shifting from subtract to add position the twelve-tooth wheel carrier 177 and, therefore, notch 192, move forward a greater distance than their ten-tooth counter parts which results in that the latch 191 which is controlled by the nose 137 of a link 120 in a ten-tooth section must also be moved a greater distance than a ten-tooth latch to prevent the former from being re-engaged with notch 192 when the carrier reaches its add position. To this end, the nose 137 of the link 120 controlling said latch is elongated to withdraw said latch a greater distance. It will be understood that whereas in the present instance it is the nose 137 of the highest order link 120 that is elongated due to the positioning of the twelve-tooth wheels in units order, in

those instances in which the twelve-tooth wheels are situated in some other order it is the nose 137 next lower order that is elongated.

The twelve-tooth wheels 175 and 176 are provided each with a carry tooth 184 (Figs. 5 and 6) for cooperation with a carry pawl 195 in withdrawing the latch 132 or 125 of next higher order through a link 196 and for arresting the wheels at zero in totaling operations. These devices are of the same sort as their ten-tooth counter parts except in size and proportion to one another.

While there is above described but one embodiment of the invention, it is possible to produce still other embodiments without departure from the inventive concept above disclosed, and it is, therefore, desired that only such limitations shall be imposed on the appended claims as are stated therein, or required by the prior art.

What I claim as new, and desire to secure by Letters Patent, is:

1. In an accumulator of the class described, a parallel linkage in each of several denominational orders thereof, a pair of intermeshing wheels supported by each said linkage, a non-parallel linkage in one or more orders thereof, a pair of intermeshing wheels supported by each latter linkage, the wheels of the last said pair having a different number of the teeth than the wheels of the first said pair but all of the wheels being of substantially the same pitch, a rocking member common to all of said linkages, said member acting through said linkages to shift the wheels of a pair through linear distances relative to one another, and an eccentric connection between each non-parallel linkage and said rocking member whereby the wheels supported by each last said linkage are shifted different linear distances relative to one another than the wheels supported by a parallel linkage.

2. In one or more denominational orders of an accumulator of the class described, a linkage comprising an upper carrier and a lower carrier, a pair of intermeshing pinions, one supported by the upper carrier and one by the lower, a rocker common to all the orders of the accumulator and having upper and lower pivot rods, said lower carrier being pivoted on the lower of said rods, and an eccentric on the upper of said rods and fixed to rock with said rod in unison with and through the same angles as said rocker, said upper carrier being pivoted on said eccentric so as to impart to the former by the rocking of the latter an amount of movement different from that imparted to the lower carrier.

3. In one or more denominational orders of an

accumulator of the class described, a linkage comprising an upper carrier and a lower carrier, a pair of intermeshing pinions, one supported by the upper carrier and one by the lower, a rocker common to all the orders of the accumulator and having upper and lower pivot rods, said lower carrier being pivoted on the lower of said rods, and an eccentric fast on the rocker, said upper carrier being pivoted on said eccentric so as to impart to the former by the rocking of latter an amount of movement different from that imparted to the lower carrier.

4. In an accumulator of the class described, a parallel linkage in each of several denominational orders thereof each such linkage including an upper carrier and a parallel lower carrier, a pair of intermeshing wheels supported by each pair of carriers, a non-parallel linkage in one or more orders thereof, each latter linkage including an upper carrier and a non-parallel lower carrier, a pair of intermeshing wheels supported by each pair of non-parallel carriers, wheels of the last said pair having a different number of teeth than the wheels of the first said pair, but all of the wheels being of substantially the same pitch, a rocker common to all the orders of the accumulator and having upper and lower pivot rods on which the parallel carriers are pivoted, the lower non-parallel carriers also being pivoted on the lower rod, an eccentric fast on the rocker in each of said one or more orders, each non-parallel upper carrier being pivoted on a said eccentric so as by the rocking of said rocker to shift the wheels supported by the non-parallel carriers through linear distances relative to one another different from those through which the wheels supported by the parallel carriers are shifted, a frame bar shifted by said rocker through the same linear distances as the parallel carriers, means to put all of the carriers under spring tension to rock about their pivots to effect a carry, a shoulder on each upper parallel carrier to engage said frame bar and limit the rocking movement of said carrier to one tooth space of the rack, and a shoulder on each non-parallel upper carrier but having two levels, one to engage said bar when the accumulator is set for addition and the other to engage said bar when in shifting the accumulator the non-parallel carrier is by its different linear movement moved relative to said frame bar both in the same direction as said linear movement and in a vertical direction.
